UNITED STATES PATENT OFFICE.

DANIEL F. CARMICHAEL, OF MINNEAPOLIS, MINNESOTA.

SEPARABLE FASTENER.

1,284,288.

Specification of Letters Patent. Patented Nov. 12, 1918.

Application filed July 5, 1917. Serial No. 178,813.

To all whom it may concern:

Be it known that I, DANIEL F. CARMICHAEL, a citizen of the United States, residing at Minneapolis, in the county of Hennepin and State of Minnesota, have invented certain new and useful Improvements in Separable Fasteners; and I do hereby declare the following to be a full, clear, and exact description of the invention, such as will enable others skilled in the art to which it appertains to make and use the same.

My invention has for its object to provide an extremely simple and highly efficient separable fastener, intended for general use, but especially adapted for use in connection with wearing apparel.

To the above end, generally stated, the invention consists of the novel devices and combinations of devices hereinafter described and defined in the claims.

In the accompanying drawings, which illustrate the invention, like characters indicate like parts throughout the several views.

Referring to the drawings,

Figure 1 is a perspective view of the members of the separable fasteners pulled apart;

Fig. 2 is a plan view of the socket plate; Fig. 3 is a view in section taken on the line 3—3 of Fig. 2;

Fig. 4 is a plan view of the head plate;

Fig. 5 is a view in section taken on the line 5—5 of Fig. 4;

Fig. 6 is a plan view of the separable fastener showing the first step in moving the members thereof into interlocking engagement;

Fig. 7 is a view in section taken on the line 7—7 of Fig. 6;

Fig. 8 is a view corresponding to Fig. 7, but showing a further step in moving the members of the separable fastener into interlocking engagement;

Fig. 9 is a plan view of the separable fastener with the members thereof interlocked;

Fig. 10 is a view in section taken on the line 10—10 of Fig. 9;

Fig. 11 is a plan view showing a modification of the separable fastener and illustrating the first step in moving the members thereof into interlocking engagement;

Fig. 12 is a view, partly in edge elevation

and partly in section taken on the line 12—12 of Fig. 11;

Fig. 13 is a view corresponding to Fig. 12, with the exception that the members are in interlocking engagement;

Fig. 14 is a plan view of the socket member shown in Figs. 11, 12 and 13; and

Fig. 15 is a view in section taken on the line 15—15 of Fig. 14.

Referring first to the separable fastener shown in Figs. 1 to 10, inclusive, the numeral 16 indicates a socket plate or member provided with a slot 17 having an expanded end and a contracted end. A portion of the metal cut to form the expanded end of the slot 17 is bent laterally inward to form a stop 18 which extends transversely with respect to said slot. Fitted within the socket member 16, is an endless retaining spring 19 that is bent inwardly upon itself to form a substantially U-shaped section so arranged that its intermediate portion extends transversely across the expanded end of the slot 17. A plurality (as shown four) of circumferentially spaced sewing holes 20 are formed in the peripheral edge portion of the socket plate 16. Three of these sewing holes 20 are formed by cutting the socket plate 16 on three sides of each of said sewing holes to form clips 21, that are folded inward onto the retaining spring 19 to secure the same to the socket plate 16.

The other member of the separable fastener comprises a head plate 22 having an integrally formed downwardly and outwardly curved neck 23, which terminates in a head 24. The neck 23 and head 24 have the same contour as the slot 17 and which head extends in a plane that is parallel to the head plate 22. Formed in the head plate 22, are a plurality of sewing holes 25, and pressed from the intermediate portion of the head 24 is a retaining lug 26. The members 16 and 22 of the separable fastener are secured, one to each of the two flaps of a garment, or other article, by stitching through the respective sewing holes. It is, of course, understood that in place of securing the separable fastener to an article by stitches, clips, or other suitable means may be used.

In connecting the members of the separable fastener, the same are placed in relation

to each other, as shown in Figs. 6 and 7, and in which position, the lock lug 26 bears upon the retaining spring 19. Then, by pressing the two members of the separable 5 fasteners together, the retaining spring 19 is depressed and the neck 23 moved into the contracted end of the slot 17 and the head 24 moved through the expanded end of said slot, as shown in Fig. 8. While the retaining 10 spring 19 is held depressed, the head plate 22 of the separable fastener is moved with respect to the socket plate 16 to draw its neck 23 into the contracted end of the slot 17 and thereby interlock the head 24 15 with the socket plate 16. This movement of the head plate 22 carries the lock lug 26 out of engagement with the retaining spring 19 and allows the same to move into the path of movement of said lug, as shown in Fig. 20 10. The tension of the spring 19 is very light and simply prevents the members of the separable fastener from separating under slack.

From the above description, it is evident 25 that when the members of the separable fastener are interlocked, the neck 23 of the head plate 22 engages the transverse wall in the contracted end of the slot 17 as a positive stop on which the pulling strain between 30 the members of the separable fastener comes. To release the members of the separable fastener, a reverse movement from that required to carry the head 22 into the contracted end of the slot 17, will cause the lock 35 lug 26 to cam the retaining spring 19 out of its path of movement and permit the head 24 to move into the expanded end of said slot. In the separating movement of the members of the separable fastener, the head 40 24 engages the stop 18 which properly positions the same together with the neck 23, for removal through the slot 17.

Referring now to the separable fastener shown in Figs. 11 to 15, inclusive, the socket plate and head plate are indicated by the numerals 27 and 28, respectively. The socket plate 27 is of the same form as the socket plate 16, has a slot 29, which corresponds in form to the slot 17, and is provided with 45 sewing holes 30. The retaining spring 31 for the socket plate 27 is integral therewith, extends from the expanded end of its slot 29, and is formed from the material cut from said socket plate to form the slot 29. 50 As shown, the retaining spring 31 is bent upon itself to give the same the required resiliency and its free end is located at substantially the same point as the transverse section of the retaining spring 19. 55 The head plate 28 is of annular form with circumferentially spaced sewing holes 32 and has an axially located neck 33, which terminates in a head 34 having a lock lug 35. The movements required to carry the 60 head 34 into interlocking engagement with

the contracted end of the slot 29 are the same as those of the previously described separable fastener, and the retaining spring 31 engages the lock lug 35 to yieldingly hold the members of said separable fastener interlocked. In separating the head plate 28 from the socket plate 27, the head 34 engages the spring 31 at its junction with the socket plate 27 as a stop to properly position said head for removal from the slot 29.

The members of the different forms of separable fasteners shown in the drawings, are interchangeable, or in other words, the socket plate 16 may be used in connection with the head plate 28, and likewise, the socket plate 27 may be used in connection with the head plate 22. The separable fasteners are well adapted for use in connection with light fabrics for the reason, very little force is required in connecting and separating the members thereof.

What I claim is:—

1. A separable fastener comprising a socket plate and a head plate, said socket plate having a slot with a contracted end and an expanded end, said head plate having a neck terminating in a head adapted to be inserted through the expanded end of the slot and interlocked with the contracted end thereof, and an endless retaining spring 90 mounted in the socket plate and extending across said slot and engageable with the head plate to yieldingly hold the head plate and the socket plate interlocked.

2. A separable fastener comprising a socket plate and a head plate, said socket plate having a slot with a contracted end and an expanded end, said head plate having a neck terminating in a head adapted to be inserted through the expanded end of the slot and interlocked with the contracted end thereof, said head plate having a lock lug and said socket plate having a retaining spring the end of which is engageable with the adjacent face of the lock lug to yieldingly hold the head plate and the socket plate interlocked.

3. A separable fastener comprising a socket plate and a head plate, said socket plate having a slot with a contracted end and an expanded end, said head plate having a neck terminating in a head adapted to be inserted through the expanded end of the slot and interlocked with the contracted end thereof; said head plate having a lock lug, a retaining spring mounted in the socket member and engageable with the lock lug to yieldingly hold the head plate and socket plate interlocked, a clip integral with the socket plate for securing the retaining spring thereto, and a sewing hole in the socket member at the fixed end of the clip.

4. A separable fastener comprising a socket plate and a head plate, said socket plate having a slot with a contracted end

and an expanded end, said plate having a neck terminating in a head adapted to be inserted through the expanded end of the slot and interlocked with the contracted end 5 thereof, said head plate having a lock lug and said socket plate having a retaining spring engageable with the lock lug to yieldingly hold the head plate and the socket

plate interlocked, and a stop for positioning the head in the slot. 10

In testimony whereof I affix my signature in presence of two witnesses.

DANIEL F. CARMICHAEL.
